Primary Examiner — Mitchell I. Siegel*(74) Attorney, Agent, or Firm* — Banner & Witcoff, Ltd.(57) **CLAIM**

The ornamental design for a hockey stick, as shown and described.

DESCRIPTION

FIG. 1 is a front, left perspective view of a hockey stick showing my new design;
FIG. 2 is a left side view thereof;
FIG. 3 is a right side view thereof;
FIG. 4 is a front view thereof;
FIG. 5 is a rear view thereof;
FIG. 6 is a bottom view thereof;
FIG. 7 is a top view thereof;
FIG. 8 is a cross-sectional view at 8-8 in FIG. 2 thereof;
FIG. 9 is a cross-sectional view at 9-9 in FIG. 2 thereof;
FIG. 10 is front, right perspective view of a left-handed hockey stick, which mirrors that of the right-handed hockey stick of FIGS. 1-9;
FIG. 11 is a right side view thereof;
FIG. 12 is a left side view thereof;
FIG. 13 is a front view thereof;
FIG. 14 is a rear view thereof;
FIG. 15 is a bottom view thereof;
FIG. 16 is a top view thereof;
FIG. 17 is a cross-sectional view at 17-17 in FIG. 11 thereof; and,
FIG. 18 is a cross-sectional view at 18-18 in FIG. 11 thereof.
